FORK OR SIMILAR ARTICLE OF FLATWEAR

Edward J. Conroy, Meriden, Conn., assignor to The International Silver Company, Meriden, Conn., a corporation of Connecticut

Filed Mar. 14, 1962, Ser. No. 69,266

Term of patent 14 years

(Cl. D54—12)

FIG. 1.

FIG. 2.

FIG. 3.

FIG. 4.

FIG. 5.

FIG. 1 is a front elevational view of a fork, showing my new design;

FIG. 2 is a rear elevational view;

FIG. 3 is a side elevational view;

FIG. 4 is an enlarged cross sectional view taken on line 4—4 of FIG. 1; and

FIG. 5 is an enlarged cross sectional view taken on line 5—5 of FIG. 1.

The design is intended for use on sets comprising forks, spoons, knives and similar articles of flatware.

I claim:

The ornamental design for a fork or similar article of flatware, substantially as shown and described.
